UNITED STATES PATENT OFFICE.

GEORGE LAMBERT LONSDALE, OF WANGAREE, NEAR SYDNEY, AUSTRALIA, ASSIGNEE
OF ONE-HALF TO ARTHUR ERNEST ACKERS, OF SYDNEY, AUSTRALIA.

PROCESS AND APPARATUS FOR COOLING SUGAR AND LIKE MATERIAL.

Application filed October 19, 1927, Serial No. 227,333, and in Australia May 31, 1926.

This invention has reference to a process and apparatus for cooling sugar and like material and is particularly directed to the cooling of icing sugar after it leaves the mill.

It is well known in the art that during the pulverizing of the sugar to produce the finer sugars, as icing sugar, the said sugar generates considerable warmth and if the sugar is packed in this condition it forms nodules of varying sizes and also may form a solid.

This is primarily due to the fact that the sugar being warm becomes hydroscopic and therefore absorbs moisture from the atmosphere which binds the sugar particles together and sugar so conditioned loses the value owing to time entailed in pulverizing it to obtain a powder form.

The present invention has been devised with the object of cooling the pulverulent sugar before packing so that when bagged or otherwise packed it will remain in the finely divided state and will not form lumps through any of the conditions herein set out.

In order to readily understand the invention, reference will now be made to the accompanying drawings in which:

Figure 1 is a view in side elevation partly in section of sugar cooling apparatus constructed according to this invention.

Figure 2 is an end view thereof.

Figure 3 is a detail view showing connection for water circulation, and

Figure 4 is a detail view showing agitating means for the sugar.

A cooling system as conceived in this invention comprises a rotating cylinder 5 having a water jacket 6 which is provided with an inlet and outlet pipe 7 and 8 respectively, for maintaining a constant water circulation, the water coming in from a main service 8^a to one end of the cylinder 5 passing through and forming the water jacket 6 and passing out to a suitable water cooling system.

Disposed on the water feed pipe line 7 is a valve 9 for controlling pressure and between said valve 9 and the cylinder 5 is a water-tight joint 10, one part 11 of which is fixed to the water feed pipe 7 and rotates with the cylinder 5 while the other part of the joint is held to the pipe 7^a connecting the water supply, a suitable packing 12 being disposed between the fixed and moving portions of the joint to prevent leakage of water.

The water tight joint 10 is obtained by

providing the pipe line 7 with a flange member which passes over the flange 14 of the fixed portion, a ring member 15 being secured at several points by means of bolts or studs 16 to the flange 13, thus the packing 12 is drawn tightly between the faces of the flange member 14 and ring member 15.

The cylinder 5 is mounted inside runners 17 which are maintained in spaced relationship by means of stay rods 18 and disposed centrally of the cylinder is a toothed wheel 19 meshing with a driving pinion 20 for rotating the cylinder 5.

The runners 17 above described move over rollers 21 which are retained in bearings 22 on suitable foundations 23 and as the cylinder 5 operates at an angle as shown to feed the sugar through by gravity means are provided for taking the thrust.

This comprises the provision of a roller or rollers 24 at the feeding end 25 of the cylinder 5, such roller 24 being adapted to engage with a flange 26 on the forward runner as 17^a the arrangement being such that all pressure is taken on the said roller.

In order to prevent dust passing from the cylinder 5 during the cooling, discs 27-28 are placed over each end of the cylinder 5 and in the case of the disc 27 at the forward or feeding end, this is held to the chute 29 which delivers the sugar from the mill, whilst the disc 28 at the delivery end of the cylinder 5 is held to the delivery chute 30 which diverts the sugar to any convenient bagging place by means of a conveyor or the like.

In order to continually disturb the sugar during the cooling process and prevent the formation of masses, blades 31 are arranged on the inside of the cylinder 5, said blades 31 being adapted to pick up the sugar and deliver it in thin vertical streams to the cooling surface.

Cooling sugar or the like in the manner herein set out is characterized in that the said sugar does not regain any of the qualities which cause it to lump and furthermore, a very large cooling surface is presented to the sugar at each revolution of the cylinder 5.

The advantage of this type of cooling system is such that the operation is a continuous one, and by controlling the speed at which the cylinder 5 rotates the quantity of sugar is also controlled.

What I claim as my invention and desire to secure by Letters Patent is:—

1. Apparatus for cooling sugar and like material comprising a rotatable water jacketed cylinder, runners on said cylinders, stay rods connecting said runners, a toothed pinion on said cylinder meshing with a toothed pinion on a driving shaft, a thrust roller or rollers in contact with a runner at the feed end of said cylinder, sugar feeding means to the said cylinder and discharge means to said cylinder, and sugar agitating means within the said cylinder.
2. The process of cooling sugar to remove the heat incident to its pulverization comprising forming the sugar to be treated successively in piles by pouring it from one position to another on a cooling surface, causing it to fall in a thin film during pour-

ing, for the purpose of air cooling the sugar, and causing the order of deposit of the pulverulent particles to be alternately reversed, so that the sugar on the top of the first pile will be at the bottom of the next, thus promoting uniform cooling throughout the entire mass of the sugar.

3. In apparatus for cooling sugar, a rotatable jacketed cylinder in which said sugar is treated, the inner wall of said cylinder being formed with hollow ribs extending longitudinally of said cylinder, the hollows of said ribs being freely open to the jacket space, and means for admitting circulatory cooling medium to said jacket space.

Signed at Sydney, New South Wales, Australia, this first day of September, 1927.

GEORGE LAMBERT LONSDALE.
